(57) **CLAIM**

The ornamental design of an autonomous delivery vehicle, as shown and described.

DESCRIPTION

FIG. 1 is a front perspective view of the autonomous delivery vehicle, showing my new design;

FIG. 2 is back perspective view thereof;

FIG. 3 is a front view thereof;

FIG. 4 is a back view thereof;

FIG. 5 is a left side view thereof, right side view being a mirror image;

FIG. 6 is a top plan view thereof; and,

FIG. 7 is a bottom plan view thereof.

The broken line portions of the figure drawings are included to show portions of the article that form no part of the claimed design.

1 Claim, 7 Drawing Sheets
